LENS GRINDING MACHINE

Alexander H. Roehr, near Dayton, Ohio, assignor
to David E. Jordan, Dayton, Ohio

Application March 8, 1940, Serial No. 323,023

14 Claims. (Cl. 51—92)

This invention relates to lens grinding machines and more particularly to the type of such machines wherein the lens is ground on the peripheral edge of a circular grinding stone.

Heretofore it has been the practice for the operator to hold in his hands the lens to be ground in proper position in engagement with the grinding stone in performing the lens grinding operation.

It is the primary object of the invention, therefore, to provide mechanical means for holding the lens in position adjacent the grinding stone, which means is readily manipulatable by the operator to engage a lens held thereby with the grinding wheel and to move the lens relative to said wheel so that different portions of the lens may be engaged therewith as desired during the grinding operation.

It is a particular object of the invention to provide means for supporting the carrier above the grinding stone in such a manner that it may be moved toward and away from said stone vertically. To this end there is provided a carrier which includes a cross head swingable about a pivotal support above the grinding wheel to enable the lens to be moved vertically respecting the latter.

It is a further object to provide means for enabling movement of the carrier relative to its support in a direction tangential to the periphery of the stone. To this end a part of the carrier is made slidable in the cross head.

The device further includes clamp means for readily and quickly clamping the lens to the carrier, said clamp means having provision for the accommodation of varying lengths of lenses.

The device further includes means for positively holding the carrier in a raised position away from the grinding stone when the same is out of use.

Further objects and advantages of the invention will appear more fully as the description of the invention progresses in conjunction with the accompanying drawing, in which:

Figure 1 is a side elevation of a device embodying my invention.

Figure 2 is a front end elevation of the same.

Figure 3 is a vertical sectional view through a portion of the carrier and clamp means.

Now referring to the drawing for a detailed description of the invention, the grinding wheel 1 is fixed to a shaft 2 mounted in suitable bearings 3 secured to frame members 4. The grinding wheel 1 is driven from a suitable source of power through a pulley 5, also fixed to the shaft 2.

Suitably secured to the horizontal frame members 4 are upright or vertical frame members 6, and opposite ends of a shaft 7 are journaled in the upper ends of said frame members 6. A cross head 8 is rotatably journaled on the shaft 7 and has fixed thereto, or formed integral therewith, a disc 9 provided with a notch 10 for engagement with the latch portion 11 of a latching dog 12. The dog 12 is pivotally secured to a stub shaft 13, one end of which is fixed to an extension frame member 14 secured to one of the vertical frame members 6.

The cross head 8 has a longitudinal channel or groove 15 at its under side in which the slide member, in the form of a T-rail 16, is slidable. The upper cross portion 16a of the T-rail is supported in the channel 15 by track members 17, secured to the cross head 8 by bolts 18.

Take-up strips 19 are provided at either side of the channel 15, engaging the opposing edges of the cross portion 16a and tensioned by the adjusting bolts 20 for taking up the transverse play of the slide member 16 respecting the cross head 8.

Secured to the underside of the lower cross portion 16b of the slide member 16 are spaced blocks 21 to which is secured a rail 22 by means of counter-sunk screws 23, or any other suitable means. This rail 22 provides the support for the opposed clamping members 24 and 25 which engage opposing ends of a lens, such as indicated at 26, which is to be ground upon the grinding wheel 1.

The clamping members 24 and 25 comprise metal blocks provided with buffers 24a and 25a of resilient material, such as leather or the like, to prevent bruising of the ends of lens, such as indicated at 26. The clamping members 24 and 25 are secured to the rail 22 by means of bolts 27 and 28 passing through longitudinal slots 29 in said rail.

The clamp member 24 is adjustable to different fixed positions respecting the length of the rail 22 by loosening the bolt 27 to permit movement in its slot 29, and then tightening the bolt 27 when the clamp member 24 has been moved to the desired position relative to the normal position of the clamp member 25, to accommodate the particular length of lens being ground.

The clamp member 25 is somewhat loosely retained on the rail 22 by the bolt 28 so that the latter is at all times readily slidable in its slot 29. A rod 30 is secured to the clamp member 25 and pivotally connected, as at 31, to one arm 32a

of a lever 32 fulcrumed, as at 33, to a bracket 34 secured to the rail 22.

The arm 32a of the lever projects through an appropriate slot in the rail 22. A compression spring 35 is provided on the rod 30 between the clamping member 25 and an abutment member 36 provided on the rail 22 and through an opening in which abutment member rod 30 passes. The spring 35 normally urges the clamp member 25 in a direction toward its opposing member 24.

In operation, the clamp member 24 is adjusted to a fixed position at a distance from the clamp member 25 less than the length of the lens to be ground. This adjustment is effected, as above mentioned, by loosening the bolt 27 and moving the clamp member 24 lengthwise of the rail 22 between the ends of the slot through which the bolt 27 extends, and then tightening said bolt to fix the clamp member 24 in the desired position.

The lever 32 is then actuated to move the clamp member 25 against the compression of the spring 35 by raising the handle of said lever, whereupon the lens 26 is placed between the opposing clamp members 24 and 25 and the lever 32 released to permit the spring 35 to cause movement of the clamp member 25 into tight engagement with the lens.

It will be observed that there are provided cushion members 37 at spaced points on the rail 22 for preventing injury to the lens by direct engagement with the underside of the rail 22 when said lens is clamped in position between clamp members 24 and 25. As shown, the cushion members 37 comprise straps of resilient material, such as leather or the like, surrounding the rail 22 and having their ends brought together and fastened by means of fastening means 38 passing through the ends of each cushion member 37.

In the embodiment of the invention shown, the grinding wheel 1 is provided with a peripheral groove 1a with which a lens 26 is to be engaged for producing a concave surface on said lens 26.

With a lens, such as 26, positioned between the clamp members 24 and 25, as above described, the grinding operation will be performed by causing the entire carrier to swing about the pivotal axis 7 of the cross head 8 so as to bring the undersurface of the lens 26 into engagement with the groove 1a of the grinding wheel 1. Thereupon, the slide member 16 may be reciprocated in the cross head 8 by actuation of the handle 39 secured to said slide member in such a manner as to cause the lens 26 to be moved tangentially of the grinding wheel 1 in the groove 1a.

Adjustable slide blocks 40 and 41 are provided on the cross member 16a of the slide member 16 to act as abutment members for limiting the extent of movement of the slide member 16 respecting the cross head 8. The members 40 and 41 are provided with set screws 40a and 41a respectively for enabling adjustment of said members 40 and 41 lengthwise of the slide member 16.

When it is desired to maintain the carrier in raised position so that the lens 26 is disengaged from the grinding wheel, said carrier is swung about the pivotal axis 7 of the cross head 8 in a clockwise direction, having reference to Figure 1, until the latch portion 11 of the latch dog 12 engages in the notch 10 of the disc 9 fixed to said cross head 8. The latch dog 12 may be readily disengaged from its aforesaid connection with the cross head 8 by moving the dog 12 about its pivotal axis 13 when it is desired again to swing the

carrier into position for engagement of a lens 26 carried thereby with the grinding wheel 1.

From the foregoing description, it will be seen that the invention provides a very efficient and readily manipulatable means for positively holding and positioning a lens for the grinding operation. The construction is capable of many variations within the scope of the invention as will be apparent to those skilled in the art, and I do not intend to be limited to details of structure except as the invention is defined in the appended claims.

Having thus described my invention, what I claim as new and desire to secure by Letters

15 Patent of the United States is:

1. In a device of the class described, in combination, a grinding wheel, and a lens carrier freely swingable about a fixed axis above said wheel and comprising a part reciprocable relative to said axis and transversely of said wheel, whereby to enable movement of said part toward and away from, as well as transversely of, said grinding wheel.

2. In a device of the class described, the combination with a grinding wheel of a lens carrier freely swingable about a fixed axis above said wheel and comprising a part reciprocable relative to said axis and transversely of said wheel, whereby to enable movement of said carrier toward and away from, as well as transversely of, said grinding wheel, and clamping means for holding a lens on said reciprocable part.

3. In a device of the class described, the combination with a grinding wheel of a lens carrier supported for free swinging movement about a fixed axis above said wheel and comprising a part reciprocable relative to said axis and transversely of said wheel, whereby to enable movement of said carrier toward and away from, as well as transversely of, said grinding wheel, and means releasably engageable with said carrier for locking said carrier against movement about said axis for maintaining said part withdrawn away from said wheel when the device is not in use.

4. A device as claimed in claim 3, wherein the said means comprises a pivoted latch releasably engageable with said carrier.

5. In a lens holder of the class described, in combination, a support, a pair of clamping members carried by said support and movable in opposite directions relative thereto toward and away from one another on a common line, means for adjusting one of said members to different fixed positions respecting said support and relative to the other member, yieldable means normally urging the other of said members toward the first member along said line, and actuating means associated with said second member to cause movement of the same away from said first member along said line against the action of said yieldable means.

6. A lens holder as claimed in claim 5, wherein the actuating means comprises a lever fulcrumed on said support, and a pivotal connection between said lever and said first member.

7. In a lens holder of the class described, a support, a pair of clamping members movably carried on said support, one of said members being adjustable to different fixed positions relative to said support and to the other member, a lever pivoted to said support, an abutment member on said support, a rod pivoted to said lever and connected to the other of said clamping

members, a compression spring on said rod intermediate said abutment member and said other of said clamping members for normally urging said last mentioned clamping member toward the first clamping member.

8. In a lens holder of the class described, in combination, a support having slots therein, a pair of clamping members carried by said support, each of said clamping members comprising a part movable in one of said slots, yieldable means normally urging one of said members toward the other, and actuating means associated with said first member to cause movement of said first member away from said other member against the action of said yieldable means, said means comprising a lever pivoted to said support and said lever including an arm extending through one of said slots, and means pivotally connecting the end of said arm with said first member.

9. In a lens holder of the class described, in combination, a support, a pair of clamping members carried by said support, and movable in opposite directions relative thereto on a common line toward and away from one another, means for adjusting one of said members to different fixed positions respecting said support and relative to the second member toward or away from the latter along said common line, yieldable means normally urging the second member toward the other, and actuating means associated with said second member to cause movement of said second member along said line away from said other member against the action of said yieldable means, and resilient means on said support and said clamping members for cushioning a lens held thereby.

10. In a device of the class described, in combination, a grinding wheel, a fixed axis above said wheel, a member pivoted to said axis and supported solely thereby for free swinging movement thereabout, and a lens holder supported by said member for sliding movement relative thereto and transversely of said wheel whereby to enable movement of said lens holder about said axis toward and away from said wheel and transversely of said wheel relative to said member.

11. In a device of the class described, in combination, a grinding wheel, a shaft located above and fixed relative to said wheel, a member pivoted to said shaft and supported solely by said shaft for free swinging movement thereabout, a lens holder supported by said member for sliding movement relative thereto and transversely of said wheel, whereby to enable movement of said lens holder about said axis toward and away from said wheel and transversely of said wheel relative to said member, and means releasably engageable with said member for locking said member against movement about said shaft for

maintaining said holder withdrawn away from said wheel when the device is not in use.

12. In a device of the class described, in combination, a grinding wheel, a shaft located above and fixed relative to said wheel, a member pivoted to said shaft and supported solely by said shaft for free swinging movement thereabout, a lens holder supported by said member for sliding movement relative thereto and transversely of said wheel, whereby to enable movement of said lens holder about said axis toward and away from said wheel and transversely of said wheel relative to said member, and means releasably engageable with said member for locking said member against movement about said shaft for maintaining said holder withdrawn away from said wheel when the device is not in use, and adjustable means for regulating the extent of movement of said lens holder with respect to said member.

13. In a device of the class described, in combination, a support, a pair of opposed clamping members on said support and movable in opposite directions relative thereto toward and away from one another along a common line, one of said members having limited floating movement relative to said support, and the other of said members being adjustable along said line to different fixed positions relative to the support and toward or away from the first member for varying the initial distance between said members to approximate the length of lens to be accommodated, means yieldably urging the first member toward the second and means operable upon the first member to cause movement of the latter relative to the support away from the second member against the action of said yieldable means.

14. In a lens holder of the class described, in combination, a support, a pair of clamping members carried by said support and movable in opposite directions toward and away from one another along a common line, means for adjusting one of said members to different fixed positions respecting said support and relative to the second member, yieldable means normally urging the second one of said members toward the other along said line, and actuating means associated with said second member to cause movement of said second member away from said other member along said line against the action of said yieldable means, and resilient members on the opposing faces of said clamping members for cushioning the opposing ends of a lens received between said clamping members, and resilient members on said support for cushioning engagement with the side of the lens facing the support when the lens is in clamped position thereon.

ALEXANDER H. ROEHR.
